UNITED STATES PATENT OFFICE.

MAURICE W. COLLINS, OF CHEYENNE, WYOMING.

DESIGN FOR A DESK UTENSIL—NAMELY, A PAPER WEIGHT, INKSTAND, OR SIMILAR ARTICLE.

60,487.

Specification for Design.

Patented Feb. 28, 1922.

Application filed February 7, 1921. Serial No. 443,274. Term of patent 7 years.

To all whom it may concern:

Be it known that I, MAURICE W. COLLINS, a citizen of the United States, residing in the city of Cheyenne, in the county of Laramie and State of Wyoming, have invented a new, original, and ornamental Design for a Desk Utensil—namely, a Paper Weight, Inkstand, or Similar Article, which is described in the following specification and illustrated by the accompanying drawing.

The drawing is a perspective view of a paper weight showing my new design.

I claim as my invention:

The ornamental design for a desk utensil, namely, a paper weight, inkstand, or similar article as shown.

Witness my signature at Omaha, Nebraska, February 1, 1921.

MAURICE W. COLLINS.
